UNITED STATES PATENT OFFICE

2,364,044

STEAM GENERATOR FURNACE

John Phillips Badenhausen, Philadelphia, Pa.

Application August 15, 1942, Serial No. 454,952

7 Claims. (Cl. 110—165)

This invention relates to steam generators and more particularly to a steam generator having provisions for handling ash liberated by the combustion of the fuel. In the generation of steam with pulverized fuel, such as pulverized bituminous coal, a considerable quantity of ash is released by the burning of the coal and total quantity, upon continued operation, must be taken into consideration. This ash is usually in finely divided form. It is the present practice to permit the major portion of the ash to collect on the floor of the steam generator and remove the same by raking and shoveling from time to time when a sufficient pile has been collected. This mode of handling the ash is not satisfactory and interferes with the operation of the steam generator. Other portions of the ash which are carried in the advancing stream of furnace gases are discharged from the stack, after passing through the induced draft fan. The discharge of ash into the atmosphere is objectionable. Frequent replacement of the blades or rotor of the induced draft fan is required because of the erosive action of the ash thereon. None of the apparatus heretofore provided for the removal of the ash from pulverized coal has proven wholly satisfactory.

It is the principal object of the present invention to provide, for the removal of the ash from pulverized fuel burned in a steam generator.

It is a further object of the present invention to improve the operation of steam generators by the provision of apparatus which may be quickly and easily installed in the building of new steam generators or which may be readily applied to existing installations for the removal of the ash from pulverized fuel.

It is a further object of the present invention to provide in a simple and reliable manner for the separation and removal of ash released by the burning of pulverized fuel in a steam generator.

Other objects of the invention will be apparent from the annexed specification and claims.

The nature and characteristic features of the invention will be more readily understood from the following description, taken in connection with the accompanying drawing forming part hereof, in which:

Figure 1 is a diagrammatic view illustrating the present invention, partly in elevation and partly in vertical section, the section being taken approximately on the line 1—1 of Figure 2.

Fig. 2 is a horizontal sectional view taken approximately on the line 2—2 of Fig. 1.

It will, of course, be understood that the description and drawing herein are illustrative merely, and that various modifications and changes may be made in the structure disclosed without departing from the spirit of the invention.

Referring more particularly to the drawing, the apparatus of the present invention includes a steam generator 10 of any preferred type, having fuel burners 11, to which fuel, such as pulverized bituminous coal, is supplied from a pulverizer 12. A coal bunker 13 provides for a supply of coal for pulverization.

An air preheater 14 is preferably provided for receiving the hot gases of combustion from the steam generator 10 and absorbing heat therefrom for preheating air for the delivery of fuel to the burners 11 and for the combustion of the fuel introduced through the burners 11. The air heater 14 preferably has a gas inlet 15 in communication with the steam generator 10 and a gas outlet 16. The air heater 14 also has an air inlet 17 and an air outlet 18, the air outlet 18 being connected to suitable ducts 19, 20, one duct 19 being connected to the burners 11 for supplying preheated air for introduction with the fuel into the combustion chamber 21 and the other duct 20 being connected to the pulverizer 12 for supplying preheated air to the pulverizer 12 to entrain pulverized fuel and deliver the fuel in a preheated air stream to the burners 11. A fan 22 is provided in the fuel delivery line 23 from the pulverizer 12 to the burners 11.

The steam generator 10 may be of any desired type but for the purposes of explanation a specific form of steam generator is illustrated. The steam generator shown includes a combustion chamber 21 having a top wall 24 in which the burners 11 are mounted, a bottom wall 25 which serves as a collecting floor, a front wall 26, and side walls 27, with a rear baffle 28 forming the rear wall of the combustion chamber 21. The rear baffle 28 is terminated at a suitable distance above the bottom wall or floor 25 for permitting the passage of gases therearound. The steam generator 10 shown also includes an upper transverse steam and water drum 30 and a lower transverse water drum 31 disposed rearwardly with respect to the combustion chamber 21 and having suitable riser and downcomer tubes extending therebetween for steam generation and circulation. The walls of the combustion chamber 21 are water cooled and provided with steam generating tubes extending upwardly therealong. The side walls 27 are provided with a bank of

tubes 32 and the front wall 26 with a bank of tubes 33. The rear baffle 28 has a bank of tubes 34 therein, these banks of tubes 32, 33, and 34 are respectively connected to the lower water drum 31 and to the upper steam and water drum 30.

The space to the rear of the combustion chamber is divided into a plurality of gas passes. For this purpose spaced upwardly extending baffles 35, 36 and downwardly extending baffles 37, 38 may be provided. In the upward pass between the baffle 28 and the baffle 35, a superheater 40 may be provided for superheating the steam liberated in the steam and water drum 30. In the downward pass between the baffle 35 and the baffle 37, a bank of steam generating tubes 41 extending from the drum 31 to the drum 30 may be provided. A bank of downcomer tubes 42 may be provided between the upper drum 30 and the lower drum 31 and in the downward pass between the baffle 36 and the baffle 38.

In accordance with the present invention the gas outlet 16 of the air heater 14 is connected by a suitable duct 44 to a dust collector 45. The dust collector 45 may be of any preferred type for the separation of the gases of combustion and the ash and may, if desired, be of the single or multiple cyclone type and is preferably constructed of suitable materials to withstand the effect of the temperature of the combustion gases upon their discharge from the air heater 14. The lower part of the dust collector 45 has an ash conveyor 46 connected thereto, the ash conveyor preferably being of the screw conveyor type, and driven by a conveyor motor 47. The gas outlet of the dust collector 45 is connected to an induced draft fan 50, which is driven by a motor 51, the outlet of the fan 50 being connected by a suitable duct 52 to the stack 53.

In accordance with the present invention, also, the steam generator 10 is provided with suitable agitators at a plurality of locations and preferably at the places where ash would normally have an opportunity to collect, such as, at the bottom floor 25 of the combustion chamber 21 and at the floor 54 below the air heater 14. The agitators for the collecting space on the floor 25 of the combustion chamber 21 preferably include small pipes or nozzles 60 at spaced intervals along each of the side walls 27 close to the bottom wall 25 and at spaced intervals along the front wall 26 close to the bottom wall 25. Pipes 61, having control valves 62 therein are connected to the small discharge pipes or nozzles 60 for supplying thereto fluid under relatively high pressure for high velocity discharge across the floor 25. The agitators for the collecting space on the floor 54 beneath the air heater 14 are similar to the other agitators and preferably include small discharge pipes or nozzles 63 at spaced intervals along each of the side walls of the air heater 14 close to the floor 54. Pipes 64, having control valves 65 therein are connected to the discharge pipes or nozzles 63.

The pipes 61 and the pipes 64 are connected to a suitable source of fluid under pressure, such as a tank 66, to which air under pressure of the order of 80 to 90 pounds per square inch is supplied by a compressor 67. If desired, steam could be supplied to the pipes 61 and 64 and in place of the air if the sulphur content of the fuel was at a low level.

The mode of operation will now be pointed out.

The steam generator 10 is operated in the customary manner, coal being supplied from the

bunker 13 to the pulverizer 12. Air, preheated in the air heater 14 and delivered through the duct 20 to the pulverizer 12, effects the delivery of pulverized coal and air through the duct 23 to the burners 11. The coal is burned at the burners 11, in the combustion chamber 21, additional preheated air being supplied from the air heater 14 through the duct 19 to the burners 11 for combustion.

10 The release of heat as radiant heat of combustion in the combustion chamber 21 effects steam generation in the banks of wall tubes 32, 33, and 34. The gases of combustion pass from the combustion chamber 21 at the lower rear part thereof, through the upward pass between the rear wall baffle 28 and the baffle 35, and in contact with the superheater tubes 40 for superheating the steam liberated in the steam and water drum 30. The gases of combustion then 15 travel successively down through the pass between the baffle 35 and the baffle 37 in contact with the banks of tubes 41 for heating the same by convection, upwardly through the pass between the baffle 36 and the baffle 31, and downwardly 20 through the pass between the baffle 36 and the baffle 38 in contact with the downcomer tubes 42. The gases then travel through the air heater 14, and in passing therethrough preheat the air for combustion.

25 30 The gases pass from the combustion chamber 21 and in their travel move at a relatively high velocity, of the order of two thousand to three thousand feet per minute. The velocity may decrease as the temperature decreases, to 35 a velocity of the order of fifteen hundred feet per minute but the design and operation of the steam generator are preferably such that the gases move at the higher velocity range. The flow of gases is maintained by the induced draft 40 fan 50 which discharges the gases through the duct 52 to the stack 53.

Upon the combustion of the pulverized fuel in the combustion chamber 25 the ash therein separates and tends in great part to fall towards 45 the floor 25. The ash particles have heretofore been permitted to collect on the floor 25 and have been removed therefrom from time to time by raking and shoveling. In accordance with the present invention fluid under pressure is supplied continuously or intermittently as desired and as required through the pipes 61 to the small pipes or nozzles 60 from which it is discharged at high velocity across the floor 25. Any particles of ash tending to collect on the floor 25 50 are agitated and swept from the floor 25 and from above the floor 25 upwardly into the stream of gases flowing from the combustion chamber 21. The ash particles are entrained and carried onward with the moving stream of combustion gases in its travel.

55 The same character of agitation is effective continuously or intermittently as desired and required at the floor 54 below the air heater 14. Any ash particles tending to settle on the floor 60 54 are agitated and blown from the floor and from above the floor 54 into the path of gases passing upwardly through the air heater 14.

65 The stream of gases with the ash particles entrained therein and carried therewith by flotation pass into the dust collector 45 where the 70 gases and the ash particles are separated. The ash is withdrawn at the lower part of the dust collector 45 and delivered by the conveyor 46 for disposal. The gases of combustion, freed of the solid ash particles by the dust collector 45,

are clean upon coming into contact with the blades of the induced draft fan 50 and as discharged from the stack 53 are free from ash which would otherwise be discharged into the atmosphere. All the ash is thus collected in a convenient manner and at a convenient location. The gases of combustion, freed of solid material, do not have any erosive action on the rotor of the induced draft fan 50.

I claim:

1. In combination with a steam generator having a combustion chamber with side walls and a flat bottom wall, means in the upper part of said combustion chamber for supplying pulverized coal for combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling from the combustion gases, said ash removing means including nozzles spaced along said side walls for supplying air in a plurality of high velocity jets for agitating the falling ash particles whereby said ash particles are elevated from the bottom wall and entrained in the stream of gases generated in said combustion chamber for delivery from said steam generator with the combustion gases.
2. In combination with a steam generator having a combustion chamber with side walls and a flat bottom wall, means for supplying pulverized coal for combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling by gravity from the combustion gases, said ash removing means including nozzles spaced along said side walls for supplying air in a plurality of high velocity jets for agitating the falling ash particles and elevating the same from the bottom wall for entrainment in the stream of gases generated in said combustion chamber and delivery from said steam generator with the combustion gases.
3. In combination with a steam generator having a combustion chamber with side walls and a flat bottom wall, means in the top wall of said combustion chamber for supplying pulverized coal for combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling by gravity from the combustion gases, said ash removing means including nozzles spaced along said side walls adjacent said flat bottom wall for supplying air in a plurality of high velocity jets for elevating the ash particles from the bottom wall for entrainment in the stream of gases generated in said combustion chamber and delivery from said steam generator with the combustion gases.
4. In combination with a steam generator having a combustion chamber with a top wall, side walls and a flat bottom wall, means in the top wall of said combustion chamber for supplying pulverized coal for combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling by gravity from the combustion gases, said ash removing means including nozzles spaced along said side walls for supplying air in a plurality of high velocity jets for agitating the falling ash particles whereby said ash particles are elevated from the bottom wall and entrained in the stream of gases generated in said combustion chamber for delivery from said steam generator with the combustion gases.
5. In combination with a steam generator having a combustion chamber with a top wall, a front wall, side walls, a flat bottom wall, upright baffles to the rear of said front wall providing a plurality of passes for the combustion gases, and a bottom wall at the last of said passes, means for supplying pulverized coal for combustion in said chamber, said combustion chamber having a combustion gas discharge outlet at the lower part thereof, said bottom walls providing ash collecting spaces for collecting the noncombustible ash released by the combustion of said coal, and means for removing from said steam generator the noncombustible ash released by the combustion of said coal and falling by gravity from the combustion gases to the collecting space, said ash removing means including nozzles spaced along certain of said walls for supplying air in a plurality of high velocity jets for agitating the falling ash particles whereby said ash particles are elevated from said bottom walls and entrained in the stream of gases generated in said combustion chamber for delivery from said steam generator with the combustion gases.
6. In combination with a steam generator having a combustion gas outlet conduit, an induced draft fan in said outlet conduit and a combustion chamber with a top wall, side walls and a bottom wall, means in the top wall of said combustion chamber for supplying pulverized coal from combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling by gravity from the combustion gases to the collecting space, said ash removing means including nozzles spaced along said side walls for supplying air in a plurality of high velocity jets for agitating the falling ash particles whereby said ash particles are elevated from the floor and entrained in the stream of gases generated in said combustion chamber for delivery from said steam generator with the combustion gases, and separator means in said gas outlet conduit beyond said combustion chamber for separating the entrained ash from the discharged combustion gases prior to their passage to the induced draft fan.
7. In combination with a steam generator having a combustion gas outlet conduit, an induced draft fan in said conduit and a combustion chamber with a top wall, side walls and a flat bottom wall, means in the top wall of said combustion chamber for supplying pulverized coal for combustion in said chamber, said combustion chamber having a combustion gas discharge outlet at the lower part thereof, said bottom wall providing an ash collecting space for collecting the noncombustible ash released by the combustion of said coal, and means for removing from said steam generator the noncombustible ash released by the combustion of said coal and falling by gravity from the combustion gases to the collecting space, said ash removing means including nozzles spaced along said side walls for supplying air in a plurality of high velocity jets for agitating the falling ash particles whereby said ash particles are elevated from the bottom wall and entrained in the stream of gases generated in said combustion chamber for delivery from said steam generator with the combustion gases.

ber with a top wall, a front wall, side walls, a flat bottom wall, upright baffles to the rear of said front wall providing a plurality of passes for the combustion gases and a bottom wall at the last of said passes, means in the top wall of said combustion chamber for supplying pulverized coal for combustion in said chamber, said combustion chamber having a combustion gas discharge outlet at the lower part thereof, said bottom walls providing ash collecting spaces for collecting the noncombustible ash released by the combustion of said coal, and means for removing from said steam generator the noncombustible ash released by the combustion of said coal and falling by gravity from the combustion gases to

the collecting spaces, said ash removing means including nozzles spaced along certain of said walls for supplying air in a plurality of high velocity jets for agitating the falling ash particles whereby said ash particles are elevated from said bottom walls and entrained in the stream of gases generated in said combustion chamber for delivery from said steam generator with the combustion gases, and separator means in said 10 gas outlet conduit beyond said combustion chamber for separating the entrained ash from the discharged combustion gases prior to their passage to the induced draft fan.

JOHN PHILLIPS BADENHAUSEN.
